D18,101

UNITED STATES PATENT OFFICE.

WILLIAM J. KEEF AND CHARLES WIPFLER, OF DETROIT, MICHIGAN,
ASSIGNORS TO THE MICHIGAN STOVE COMPANY, OF SAME PLACE.

DESIGN FOR A COOKING-STOVE.

SPECIFICATION forming part of Design No. 18,101, dated February 21, 1888.

Application filed June 18, 1887. Serial No. 241,801. Term of patent 7 years.

To all whom it may concern:

Be it known that we, WILLIAM J. KEEF and CHARLES WIPFLER, both citizens of the United States, residing at Detroit, in the county of Wayne and State of Michigan, have invented certain new and useful Improvements in a Design for a Stove, of which the following is a specification, reference being had therein to the accompanying drawing.

10 This design is especially intended for a range with high closet.

Referring to the accompanying photograph, A indicates the oven-top, having a crest which curves upward and outward. At each corner and at the center of the front are scrolls, between which the crest is perforated. Below this are the closet-doors B, each being curved at the outside to form a continuation of the curve of the side or end of the closet. Each 20 door has each corner ornamented with a scroll-shaped figure consisting of a center at the extreme corner and two smaller branches running from the corner. In the center of the door is an ornament composed of a central rosette, around which is a wreath, which in turn is surrounded by scroll-work. The sides of the closet are ornamented similarly to the doors, and both doors and sides start directly from the bottom and top.

30 Immediately below the base or shelf b of the closet is a bracket-pouch, C, having its surface ornamented by scrolls, below which is the pipe D, ornamented with the words "Garland Stoves and Ranges," surrounded by a wreath, and be-

35 low this are several projecting lines, d. At the sides of the pipe are two columns, d', ornamented by transverse ribs or beads. Outside of these columns are wings or brackets d", the top and bottom of which are ornamented by

40 rosettes, between which are three scrolls of different sizes, the smallest of which is in the center. Below the pipe, the columns, and wings is a base, E, ornamented with bands of plain beads at top and bottom, between which 45 is a band of ornamented scroll-work, in the center of which and at the bottom of the pipe are three openings partly surrounded by the scrolls. All of the above parts below the shelf b, for the purpose of this specification, we call 50 the "support."

Referring to the stove proper, it will be seen that the fire-door F is ornamented with a central scroll and two side scrolls extending from top to bottom of the door.

The oven-door G is ornamented with a central ornament, g, around which is a wreath, outside of which is a broader scroll-work. At the side of this is another ornament, g', consisting of a rosette partially surrounded by scrolls in which appear six openings. The 55 upper rear corner is ornamented by a series of scrolls running from the corner along the top and down the rear. The front edge is also ornamented with scrolls, the lower end terminating in a nondescript head.

65 The side of the reservoir H is ornamented with a rosette in the lower corner, from which rise sprays of leaves and flowers, and near the center is an ornament composed of a fancifully-shaped letter "G" inclosing flowers.

70 The front I of the stove has a hearth, J, below its doors, beneath which is a pouch, K.

75 The leg-base is ornamented with a series of rosettes and scrolls having in the center a grotesque face, from the mouth of which some of the scrolls start.

80 The leading features of this design are the rectangular closet surmounting the pipe ornamented by wings, the configuration and surface ornamentation of the closet and oven doors, the ornamentation of the pipe D, and the general configuration of the stove as a whole.

85 What we claim as new is—

1. The design for a stove, comprising the 85 stove-front, the leg-base, fire and oven doors, the reservoir, the high closet, and its support, all having the shape shown.

2. In a design for a stove herein shown and described, a closet having a base and top and 90 curved end plates whose outer lines run directly to the base and top.

3. In a design for a stove, the pipe ornamented by the bracket-pouch C, inclined upon one side and ornamented upon said inclined 95 side, as shown.

4. In a design for a stove, the closet-door curved at its outer edge and ornamented at each corner with a triangular-shaped ornament, as shown.

5. In a design for a stove, a stove-body sur-
mounted by the base E, ornamented with the
rosettes, scrolls, and openings, as shown.
6. In a design for a stove, the fire-door or-
namented with the central and two side scrolls,
as shown.
7. In a design for a stove, an oven-door hav-
ing its front edge curved and ornamented with
scrolls and having a corner ornamented with
scrolls, as shown.
8. In a design for a stove, a reservoir orna-

mented by a fancifully-shaped letter inclosing
flowers and having its bottom inclined, as
shown.

In testimony whereof we affix our signatures, 15
in presence of two witnesses, this 15th day of
June, 1887.

WILLIAM J. KEEP.
CHARLES WIPFLER.

Witnesses:

GEO. L. RENO,
THOS. ERNEST.
